UNITED STATES PATENT OFFICE.

HENRY C. SERGEANT, OF DENVER, COLORADO.

ROCK-DRILL.

SPECIFICATION forming part of Letters Patent No. 295,682, dated March 25, 1884.

Application filed December 4, 1883. (No model.)

To all whom it may concern:

Be it known that I, HENRY C. SERGEANT, of Denver, in the county of Arapahoe and State of Colorado, have invented a new and 5 useful Improvement in Rock-Drills, of which the following is a specification.

The invention relates to rock-drills which are operated by steam or compressed air.

The invention consists in the novel combination, with the cylinder and piston, the cylinder having supply-ports for admitting a motive agent to the cylinder on opposite sides of the piston, and an exhaust-port between the said supply-ports, and over which the piston passes 15 in its movements, of an automatic valve for controlling the admission of a motive agent to the said supply-ports, as hereinafter more fully described.

The invention also consists in a novel combination of parts, hereinafter particularly described, whereby the piston is cushioned at each end of its movement.

The invention also consists in a novel and simple combination of parts, whereby the rotation of the piston and drill-rod is effected.

The invention also consists in the combination, with the piston-rod of a rock-drill, of a cylinder-head having in its bore or interior an annular groove for the reception of a packing 30 and a tangential aperture or opening extending from the exterior of the head into said groove, and through which a packing may be introduced, as hereinafter more fully described.

In the accompanying drawings, Figure 1 represents a partly sectional side view of a rock-drill embodying my invention. Fig. 2 is a transverse section on the dotted line $x-x$, Fig. 1. Fig. 3 is a similar section in the dotted 40 line $y-y$, Fig. 1. Fig. 4 is a longitudinal section of the valve-seats, and a side view of the valve on a larger scale. Fig. 5 is a transverse section of the valve on the dotted line $z-z$, Fig. 4. Fig. 6 is a transverse section of the lower 45 or front cylinder-head and piston-rod on the dotted line 1 1, Fig. 1. Fig. 7 is a plan of the drill complete.

Similar letters of reference designate corresponding parts in all the figures.

A designates the back of the drill, which is 50 of ordinary construction, and which is secured,

in the usual way, to a tripod or column (not here shown) by a bolt, a .

B designates the cylinder, which is movable lengthwise of the back in ways or grooves b , 55 formed or provided in the back A; and C designates the feed-screw, which is mounted in a bearing, b' , fixed to the back A, and which may be turned by a handle, C'. The feed-screw engages with a nut, b^2 , secured in the cylinder B, and by turning the screw in one direction or the other the cylinder and all parts carried thereby are fed forward or moved back in a well-understood manner.

D designates the piston, which is provided 65 with any suitable ring-packing, and which, as here represented, is formed integral with the piston-rod D'. This piston-rod D' works through the lower or forward head, B', of the cylinder B, and carries at its lower or forward 70 end a drill-chuck, D'', which may be secured upon the piston-rod D', or formed integral therewith. When the chuck and the piston are both formed integral with the rod D', I divide the forward head, B', axially or form it in 75 two longitudinal halves, as best shown in Fig. 9, the two halves or sections being securely held together by bolts c to form the head.

The upper or back head, B'', of the cylinder consists of a solid and flat piece or disk of 80 metal, made slightly larger in diameter than the cylinder B, and rabbeted at its periphery, so as to project slightly into the cylinder and to slightly overlap the end of the cylinder, as shown in Fig. 1.

E designates a piece of metal approximately 85 annular in shape, and made entirely separate from and independent of the head B'', and formed with lugs or ears, through which are 90 inserted bolts, c' , whereby the piece E is immovably secured to the cylinder. The piece E has a hole, c^2 , through it for the passage of the feed-screw C, and as said piece is secured immovably and rigidly to the end of the cylinder it serves to retain the nut b^2 in its place 95 in the cylinder, as shown in Fig. 1. The piece E is bored out to the size of the head B'', and has within it an elastic cushion, E', of rubber or analogous material, which is externally about as large as the head B'' and rests in contact therewith. This cushion is preferably 100 annular, so that when compressed in a direc-

tion lengthwise of the cylinder it may crowd or expand inward.

5 F designates a follower, which is formed with an annular rabbet or shoulder, c³, and enters the bore of the piece E. The head B' and follower F are connected by bolts F', (best shown in Fig. 9,) and the cushion E' serves to deaden a blow of the piston on either head B' or B². When the piston strikes the lower head 10 B', the latter moves outward slightly and the follower F is moved inward, it being cushioned on E'. When the piston strikes the head B², the latter yields and moves outward slightly, it being cushioned on E'.

15 It will be observed that, inasmuch as the piece E is rigidly secured to the cylinder, it cannot yield, and said piece therefore forms a guide wherein the head B² can move outward and the follower F can move inward, the 20 cushion E' being confined between the head and follower in the guide E.

The piston D is formed with or has secured to it an extension or head, D³, which is of a size to work freely in the cylinder, and is 25 somewhat longer than the length of piston-stroke. This head or piston-extension D³ is grooved spirally from end to end on its exterior, and the grooves are preferably ratchet-shaped in cross-section, as shown in Fig. 2.

30 G designates a spring-actuated movable nut-section, which, as here shown, consists of a cylindric piece fitted in a socket or slideway, B³, which projects from the side of the cylinder, as shown in Figs. 2 and 9. The inner end of 35 the nut G is concave, so as to approximate to the circumference of the piston-extension D³, as shown in Fig. 2, and in the inner end or face of said nut-section are teeth which are adapted to engage with the spiral grooves of 40 the piston-extension, as also shown in Fig. 2. It will be observed that the center of the nut-section G is not radial to the piston-extension D³, and that a line drawn through the center of said section would be tangential to a circle 45 smaller in diameter than the said piston-extension. This arrangement enables me to make the nut-section of sufficient size to engage with several of the spiral grooves and still have the faces of the teeth of the nut-section and the corresponding faces of the 50 spiral grooves approximately radial to the piston-extension D³. If such faces of the teeth and grooves were not radial or approximately radial to the piston-extension D³, a stronger 55 spring would be required to prevent the nut-section being forced outward by the action of the piston-extension in its backward movement. The outer end of the socket B³ is closed by a plug, d, and between the inner end of 60 the plug and the nut-section G is arranged a spring, d', the nut-section being hollow, so as to receive the spring within it. The nut-section G may therefore be moved outward or away from the piston-extension D³ against the 65 force of the spring d', and by such movement the teeth of the nut-section will be entirely disengaged from the grooves of the piston-ex-

tension D³; but when the nut-section is relieved of outward pressure the spring d' will return it into engagement with the piston-extension D³. 70

On the nut-section G is a shoulder, d², which, by coming against a shoulder, d³, in the socket B³, limits the inward movement of the said nut-section and forms a stop therefor. The 75 length of the nut-section G inward of the shoulder d² is such that when the nut-section is in its inward position its inner end will not press upon the piston-extension and tend to force the latter against the opposite side of 80 the cylinder, although the teeth of the nut-section will be in strong engagement with the spiral grooves. In Fig. 2 it will be seen that the shoulder d² is against the shoulder d³, and yet the surfaces of the teeth of the nut-section 85 are out of contact with the surfaces of the grooves of the piston-extension D³, although the said teeth extend into and are in engagement with said grooves.

Although I consider the stop for preventing the nut-section G from pressing against the piston-extension D³ as very desirable, still it is not indispensable, and the nut-section might be made in the form of a straight cylinder destitute of a shoulder. The cylinder 90 is provided with supply-ports e-e', and the steam or other motive agent enters the cylinder through the port e' to produce the forward working-stroke of the piston D. Between the piston D and the piston head or extension D³ 95 is an annular groove or recess, e*, which permits the steam to pass from the port e' entirely around the piston, and enables the steam to pass freely through all the grooves of the piston-extension D³ to the back end thereof. Before the piston commences its forward or working stroke the steam, acting upon the inner 100 end of the nut-section G, forces the latter back or outward into its socket B³, and entirely disengages the teeth of the nut section from 105 the grooves of the piston-extension D³. The piston is then forced directly forward by the steam-pressure behind it, the nut-section G being held out of engagement with the grooves of 110 the piston-extension D³ during its whole forward movement. As soon as the pressure behind the piston is relieved by the opening of the exhaust, and before the piston commences 115 its backward movement, the nut-section G is forced inward by the spring d', so that its teeth enter the spiral grooves of the piston-extension D³, and during the backward movement of the piston the piston-rod and piston are turned by the engagement of the spiral 120 grooves of the piston-extension with the nut-section G. During the whole backward movement of the piston the nut-section is supported by the shoulders d² d³, and hence the said nut-section does not force the piston-extension against the opposite side of the cylinder and 125 produce friction and wear.

In the plug d, I have shown an opening, d⁴, which gives free vent to the socket B³, and prevents the nut-section from being retarded in

- its outward movement by pressure behind it, or retarded in its inward movement by the formation of a partial vacuum behind it. The plug d might be imperforate; but the nut-section would then be less active in its movements, and a stronger spring, d' , would be necessary. When the nut-section G is forced outward, its outer end closes against the plug d and prevents the escape of steam through the aperture d' . Not only does the nut-section G , operating as described, form a more simple and effective rotating device than any heretofore used, but the forcing back and holding of the nut-section G out of all contact with the piston-extension D' during the working-stroke frees the piston entirely from all connection with the rotating device and enables it to be operated with less friction. The piston may be readily turned by hand in the direction of the arrow shown in Fig. 2, as the nut-section G will yield readily when the inclined faces of the grooves on the piston-extension D' act upon the inclined faces of its teeth.
- B^4 designates the valve-chest, to which steam or other motive agent is admitted by the pipe f , and H designates the valve whereby the admission of steam to the ports e e' is controlled. The steam from the pipe f enters an annular belt or recess, f' , in the valve-chest, and thence passes, under control of the valve H , to the port e or the port e' . The valve H is made in the form of a double puppet-valve, and is adapted to close upon either of the seats e^2 e^3 , between which it works. The valve has but a slight movement, and, as shown in Figs. 1 and 4, has just moved to the left to close on the seat e^2 and open the seat e^3 to admit steam to the port e' ; but the piston has not yet commenced its forward movement, it being in its rearmost position. The position of the valve is the same in Figs. 1 and 4. The seats e^2 e^3 , as here shown, are formed on the adjacent ends of tubular pieces H' H^2 . (Best shown in Fig. 4.) These are both inserted into the valve-chest B^4 from one end thereof, and the end is then closed by a plug, f^2 . The end of the piece H' bears against a shoulder, f^3 , and a shoulder on the exterior of the piece H^2 bears against a shoulder, f^4 , in the valve-chest. The distance apart of the seats e^2 e^3 is thus determined. The valve H has arms or webs f^5 , projecting from opposite sides into the seat-pieces H' H^2 , and serving to properly guide the valve without materially interfering with the free passage of steam through the seats; and at the outer ends of these webs or arms f^5 , I have shown small disks f^6 , against which the steam strikes or impinges as it passes to the one side or the other.
- The cylinder is provided between the two supply-ports e e' with an annular exhaust belt and port, g g' , from which extends an exhaust-pipe, g^2 . (Shown in Figs. 3 and 9.) This exhaust is unprovided with any valve, and is always open to the atmosphere, except while the annular port g' is covered by the piston in its movements.

The operation of the valve H is as follows: As before stated, the valve H has just moved to close the seat e^2 and admit steam through the seat e^3 and port e' ; but the piston D D' has not yet moved. At this time the cylinder B forward of or to the left of the piston D is open to the atmosphere through the exhaust-port g' and belt g . Consequently there is but a very slight pressure on the left side of the valve H , and said valve is held strongly against the seat e^2 by the pressure of steam on its right side. The steam, rushing to the right through the seat e^3 and striking against the disk f^6 , has a tendency to draw the valve away from the seat e^2 , but cannot do so while the exhaust from the cylinder is open to the atmosphere. The piston D is now forced forward under full pressure of steam; but as soon as it covers the exhaust-port g' the low steam remaining in the forward end of the cylinder is trapped and compressed to such an extent as to create a pressure on the left side of the valve H . The pressure thus created is not nearly so great as the pressure on the right side of the valve; but it relieves the valve to such an extent that the "drawing" force produced by the steam striking on the disk f^6 is sufficient to move the valve to the right and open the seat e^2 . The valve H is thus moved to the right and steam admitted through the seat e^2 just before the piston completes its stroke; but the momentum, aided by pressure on the back of the piston, causes the drill to strike with full force, and steam acts on the piston to make the return-stroke. The piston, in its forward stroke, having passed beyond the exhaust-port g' , there is a free exhaust from the right hand of the piston D during its return-stroke until it covers and passes the exhaust-port g' ; but as soon as this occurs the steam is trapped on the right-hand side, or back of the piston, and compressed until it relieves the valve H sufficiently to allow it to be drawn to the left by the action of the steam, whereupon the operation is repeated. At each stroke of the piston the valve moves before the completion of movement of the piston, and therefore there is no liability of the piston striking violently against the heads of the cylinder.

In order to pack the piston-rod D' in the head B' , I form in the head an annular groove, h , and a hole or aperture, h' , tangential to said groove, as best shown in the transverse section, Fig. 6. The outer end of the tangential aperture h' is closed by a plug, h^2 , and when said plug is removed a strip or piece of flexible packing, h^3 , inserted through the aperture h' , will follow the groove h , and on being forced in will be compacted tightly in the groove and round the rod D' . The strip or packing may be forced or driven in through the aperture h' with a punch, and whenever the packing becomes worn and there is any leakage around the rod the plug h^2 is removed and additional pieces of packing are driven in until the packing is tight.

When the head B' is divided, as here shown, the parts may be separated to permit of the worn-out and worthless packing being removed from the groove *h*; but such clearing 5 out of the groove is not necessary, as packing may be driven in from time to time to maintain a tight joint around the rod D'.

The drill-rod I is fitted in a socket in the chuck D², and is clamped therein by means of 10 two bolts, I', the heads *i* of which are adapted to fit the drill-rod, and are caused to clamp it tightly by screwing up their nuts *i'*; but as this chuck is the subject of another application for 15 patent filed by me on the 23d day of February, 1884, No. 121,670, and is not a part of the invention herein claimed, it needs no further description here.

Although I have herein frequently referred to steam as the motive agent employed, the 20 invention is applicable to drills operated by compressed air or steam.

What I claim as my invention, and desire to secure by Letters Patent, is—

1. In a rock-drill in which the exhaust-port 25 is controlled by the piston, the combination of the ported cylinder and the piston with a fluid-controlling valve actuated by the inflowing fluid when the compression is made on the exhaust end of the cylinder, substantially as 30 shown and described.

2. The combination, with the cylinder B, having supply-ports *e e'* and an exhaust-port, *g'*, between said supply-ports, of the piston D, having a movement across and considerably 35 beyond the said exhaust-port at each stroke, and the automatic valve H, movable between the valve-seats *e'' e''*, for controlling the admission of a motive agent to said supply-ports *e e'*, substantially as described.

40 3. The combination, with the cylinder B, having supply-ports *e e'* and an exhaust-port, *g'*, between said supply-ports, of the piston D, having a movement across and considerably beyond the said exhaust-port at each stroke, 45 and the automatic valve H, movable between the valve-seats *e'' e''*, and provided with the disks *f⁶*, upon which the motive agent acts to move the valve, substantially as herein described.

50 4. The combination of the cylinder B, the

head B', the follower F, and bolts F', connecting said head and follower, the head B², having its diameter slightly larger than the cylinder, and formed with an annular rabbet, so as to enter the cylinder, the piece E, rigidly secured to the cylinder, and forming a cylindric guide, wherein the said head B² and follower F may move, and the cushion E', arranged in said guide E between the head and follower, substantially as herein described. 55

5. The combination, with the cylinder of a rock-drill, of a piston having a head or extension which is spirally grooved externally, and a spring-actuated nut-section engaging with the spiral grooves of the piston head or extension, 60 and capable of being forced back by the action of the motive agent upon its face or inner end to free it entirely from the spiral grooves of said piston head or extension, substantially as and for the purpose herein described. 70

6. The combination, with the cylinder of a rock-drill, of a piston head or extension having a spirally-grooved exterior, a spring-actuated nut-section engaging with the spiral 75 grooves of said head or extension, and capable of being forced back by the pressure of the motive agent upon its face to free it entirely from said spiral grooves, and a stop for limiting the inward movement of said nut-section, 80 substantially as and for the purpose herein described.

7. The combination of the cylinder B, having the transverse socket or slideway B³, provided with the shoulder *d³*, the spirally-grooved 85 piston-extension D³, the movable nut-section G, engaging with the grooves of said piston-extension, and provided with the shoulder *d²*, the spring *d'*, and the plug *d*, closing the outer end of said socket or slideway B³, substantially 90 as herein described.

8. The combination, with the piston-rod D', of the longitudinally-divided cylinder-head B', having the annular packing-groove *h* and the tangential aperture *h'*, substantially as herein 95 described.

HENRY C. SERGEANT.
